UNITED STATES PATENT OFFICE

WILLIAM A. ROCKENFIELD, OF ROCHESTER, NEW YORK, ASSIGNOR TO HIGH SPEED HAMMER CO. INC., OF ROCHESTER, NEW YORK, A CORPORATION OF NEW YORK

HELVE OPERATED HAMMER

Application filed February 27, 1929. Serial No. 343,171.

The present invention relates to helve operated hammers, and an object thereof is to provide a novel means of connecting the helve to a rotary hammer so as to obtain a better bearing for the hammer. Another object of the invention is to provide a helve and hammer connection embodying a strap in which the ends of the strap are connected by a bearing member. Still another object of the invention is to improve the elastic connection between the helve and its operating pitman whereby the strength of such connection is increased while the cost of manufacture is reduced. A further object of the invention is to provide an improved bearing on the support for the hammer.

To these and other ends, the invention consists of certain parts and combinations of parts all of which will be hereinafter described: the novel features being pointed out in the appended claims.

In the drawings:

Fig. 1 is a side view of the upper portion of a hammer embodying the present invention;

Fig. 2 is a vertical section through the hammer support;

Fig. 3 is an end view of the helve showing its connection with the hammer;

Fig. 4 is a section on the line 4—4, Fig. 3;

Fig. 5 is an enlarged side view partially in section of the elastic connection between the pitman and the helve; and

Fig. 6 is a fragmentary view of the helve pitman connection partially in section.

In the illustrated embodiment, 1 indicates the upper support, the lower anvil carrying frame not being shown. This upper support projects forwardly and has at the outer forward end a vertical opening formed at its top with a pocket 2. In the vertical opening is a bearing sleeve 3. Turning in the bearing sleeve is a sleeve 4 having a flange 5 at its upper end in the pocket 2. Beneath this flange 5 there is secured a worm gear 6 by pins 7, the gear lying in the pocket 2 and meshing with a worm 8 which is driven by a belt 9 from the drive pulley 10. Above the gear 6 is a washer 11 and a cover 12 secured by screws 13 holds the sleeve 4 and gear 6 in the pocket. The hammer 14 extends

through the sleeve 4 and is connected to said sleeve by a key 15 on the inner face of the sleeve projecting into a groove or way in the hammer, thus causing the hammer to turn with the sleeve 4 but permitting the hammer to slide longitudinally in the sleeve. By this construction the hammer does not reciprocate and turn in its bearings. It has a sliding movement in the sleeve which acts as a bearing, thus increasing the useful life of the bearing by cutting down wear. Further, the hammer has a more durable connection with the driving gear as a long key connects the hammer with the sleeve and the sleeve connects with the gear through a flange.

The upper end of the hammer 14 is reduced at 15^a and below this reduced portion is a surrounding flange 16. About the reduced portion is fitted a cylindrical rubber cushion 17 with a central bore for the reception of the reduced portion. The upper end of the cushion abuts the under side of the helve 18 which, in this instance, has an annular flange 19 projecting from the under face thereof to provide a pocket for receiving the upper end of the cushion to restrain the latter against lateral displacement.

For holding the hammer and helve together there is provided a flexible strap 20 formed of leather or other suitable material and having its ends secured together by a bearing. In this instance, this bearing comprises two members or plates 21 and 22 each having the hammer 14 passed therethrough beneath the flange or shoulder 16, the two plates being held together by bolts 23 and holding between them the two opposite ends of the strap 20, the bolts also passing through the straps. The plate 22 has its edges turned upwardly on opposite sides of the plate 21 so as to support the leather strap adjacent the bends. A washer 24 is interposed between the flange 16 and the upper plate 21.

This strap connection makes it possible for the user of the machine to readily replace the strap when the latter becomes worn or broken. The hammer works in a metal bearing instead of within the strap.

The helve 18 is pivoted at 25 to the support 1 and is operated through a pitman 26 from

the drive wheel 10 by means of a resilient connection as is common in this art. This resilient connection, in this instance, comprises two cushions 27 in the form of hollow rubber cylinders surrounding the pitman. The pitman having abutments 28 adjustably secured thereto and cooperating with the upper end of the upper cushion and the lower end of the lower cushion. Between the two cushions is a common abutment 29 having a central opening 30 through which the pitman 26 extends, the top and bottom faces of the common abutment being formed with seats 31 for the cushions 27. This common abutment has two trunnions or bearings 32 projected from opposite sides thereof in alignment with each other and integral with the abutment. Two plates 33 bolted on the end of the helve provide bearings for the trunnions. With this form of connection between the pitman and the helve, the parts are materially reduced. One member serves as a common abutment of the two cushions and also for a pivot pin. Friction is also reduced.

25 What I claim as my invention and desire to secure by Letters Patent is:

1. In a helve operated hammer, the combination with a pivotally mounted helve and a rotary hammer, of a connection between the helve and the hammer embodying a strap having two ends and bearing frame in which the hammer turns about its longitudinal axis having the ends of the strap detachably secured thereto, said bearing frame embodying two separate members through each of which the hammer passes, and means for detachably securing said members together with the ends of the strap between them.

2. In a helve operated hammer, the combination with a pivotally mounted helve and a rotary hammer, of a connection between the helve and the hammer embodying a strap having two ends and bearing frame on which the hammer turns about its longitudinal axis having the ends of the strap detachably secured thereto, said bearing frame embodying two separate members through each of which the hammer passes, and means for detachably securing said members together with the ends of the strap between them, the ends of the lower member extending about the ends of the upper member.

3. In a helve operated hammer, the combination with a pivotally mounted helve and a rotary hammer, of a connection between the helve and the hammer embodying a strap having two ends and bearing frame on which the hammer turns about its longitudinal axis having the ends of the strap detachably secured thereto, said bearing frame embodying two plates through each of which the hammer passes and between which the ends of the strap are passed, and bolts securing said plates together and passing through the ends of the strap.

4. In a machine of the character specified, the combination with a rotary reciprocating hammer, and a support therefor having a vertical opening which is enlarged at its upper end to provide a pocket, of a gear in said pocket, a bearing sleeve in said vertical opening and having its upper portion passing through the said gear and provided with an outer flange extending thereover and fast thereto, the hammer rotating with the bearing sleeve and free to reciprocate therein, and a driving element mounted in the support and in mesh with the said gear to impart a rotary movement thereto and to the hammer simultaneously with its reciprocation.

5. In a machine of the character specified, the combination with a rotary reciprocating hammer and a support therefor having a vertical opening which is enlarged at its upper end to provide a pocket, of a gear in said pocket, rotatable with the hammer and admitting of the latter having a free sliding movement therethrough, bearing sleeves in the said vertical opening having portions disposed on opposite sides of the said gear which is confined therebetween, and a gear mounted in the said support and in mesh with the aforesaid gear to impart a rotary movement thereto and to the hammer simultaneously with the reciprocation of the latter.
